United States Patent Office

Des. 184,758
Patented Mar. 31, 1959

184,758

PLANTER OR THE LIKE

George Munday, Miami, Fla.

Application December 4, 1957, Serial No. 48,776

Term of patent 14 years

(Cl. D35—3)

Fig. 1.

Fig. 2.

Fig. 3.

Fig. 4.

I claim:

The ornamental design for a planter or the like, as shown and described.
